Primary Examiner — George D. Kirschbaum*Assistant Examiner* — Denis Houyoux(74) *Attorney, Agent, or Firm* — Panitch Schwarze Belisario & Nadel LLP(57) **CLAIM**

The ornamental design for a receptacle cage as shown and described.

DESCRIPTION

FIG. 1 is a front, right and top perspective view of a receptacle cage in accordance with my new design; FIG. 2 is a front, right and bottom perspective view thereof;

FIG. 3 is a top plan view thereof;

FIG. 4 is a bottom plan view thereof;

FIG. 5 is a left-side elevational view thereof;

FIG. 6 is a right-side elevational view thereof;

FIG. 7 is a front elevational view; and,

FIG. 8 is a rear elevational view thereof.

The broken lines in the figures show portions of the receptacle cage which form no part of the claimed design.

1 Claim, 8 Drawing Sheets(56)
